At L'ys.

UNITED STATES PATENT OFFICE.

GUSTAV A. CARLSON, OF CHICAGO, ILLINOIS, ASSIGNOR TO THE BOYLE NEEDLE COMPANY, OF CHICAGO, ILLINOIS, A CORPORATION OF ILLINOIS.

DESIGN FOR A CAN-OPENER.

55,450.

Specification for Design.

Patented June 15, 1920.

Application filed June 26, 1919. Serial No. 307,023. Term of patent 14 years.

To all whom it may concern:

Be it known that I, GUSTAV A. CARLSON, a citizen of Sweden, residing at Chicago, in the county of Cook and State of Illinois, have invented a new, original, and ornamental Design for a Can-Opener, of which the following is a specification, reference being had to the accompanying drawing, forming a part thereof, in which—

The figure represents a perspective view of a can-opener embodying the design.

I claim:

The ornamental design for a can-opener, as shown.

GUSTAV A. CARLSON.
